UNITED STATES PATENT OFFICE

JOSEPH A. DEDOUCH, OF OAK PARK, ILLINOIS

CERAMIC FURNACE

Application filed December 22, 1928. Serial No. 327,889.

This invention relates to ceramic furnaces and the like.

Among the features of my invention is the provision of improved means for conveying pieces of work into and out of the furnace. Another feature of my invention is the provision of means for raising and inverting the upper part of the furnace, thus permitting easy repair and replacement of the lining of the heating chamber.

Another feature of my invention is the provision of improved work pressing means in conjunction with the conveyor for pressing, straightening, embossing, stamping, or designing articles while they are still on the conveyor and just after they have been taken out of the furnace.

Other features and advantages of my invention will appear more fully as I proceed with my specification.

In that form of device embodying the features of my invention shown in the accompanying drawings; Figure 1 is a view in perspective; Fig. 2 is a vertical sectional view showing a modified form of furnace; Fig. 3 is a fragmentary view in side elevation showing means for automatically reciprocating the work carrier; Fig. 4 is a vertical sectional view taken through the work pressing means; Fig. 5 is a view, in end elevation, partly in section showing the work pressing means; Fig. 6 is a view in perspective of a modified form of work conveyor; Fig. 7 is a similar view of another modified form of work conveyor; and Fig. 8 is a view in end elevation of a piece of work.

As shown in the drawings, the furnace comprises upper and lower sections 10 and 11, the latter being supported on a pipe frame 12. 13 indicates a longitudinal muffle or heating chamber extending through the furnace. The upper section of the furnace 10 is pivotally supported at its ends as indicated by 10^a between the ends of the yoke or bail 14, the latter being carried by one end of the lever 15, which, in turn, is pivotally supported at 16 on the upper ends of the vertical supporting members 17. The other end of the lever 15, as indicated by 15^a,

serves as a handle. By depressing the handle 15^a, the lever 15 is rocked to lift up the member 14 and thus raise the upper section 10 from the furnace. The pivotal mounting of the upper section 10 at 10^a permits this upper section to be inverted when raised. By thus raising and inverting the upper section of the furnace, the repairing or replacement of the lining of the muffle or furnace chamber is greatly facilitated. For example, the lining sheet on the upper surface of the muffle or heating chamber can easily be replaced or repaired. Since the upper section may be raised and inverted, such repairs and replacements can very easily be made without dismantling the rest of the furnace.

In Fig. 2, a modified form of furnace is shown in which the upper section, as indicated by 110, is hingedly attached to the lower section 111 by means of the hinges 112. As shown in Fig. 2, each furnace section is provided with a combustion chamber, the combustion chamber in the upper section 110 being indicated by 113 and the combustion chamber in the lower section 111 being indicated by 114. 115 indicates a gas burner such as a Bunsen burner for directing a gas jet or flame into the combustion chamber 113, such flame passing through the opening 116 in the side wall 117 of the section. The lower section 111 is likewise provided with a plurality of holes 116 in its side wall for the entrance of flames from similar burners (not shown). It is to be understood that similar burners may be provided for the furnace 12 in Fig. 1, such burners not being shown in the drawings. The flames or jets from such burners are directed into the furnace through the holes 18. It is to be understood that the walls of the two sections are provided with flues or openings 118 adapted to register when the furnace is closed, such flues joining the combustion chambers in the two sections to permit the passing of heated gases from the lower section to the upper section.

20 indicates a rectangular frame carrying the work supporting and conveying strands 21, here shown as wires. It is to be under-

stood that said work supporting and conveying strands need not necessarily be wires but may be strands of any suitable material. The strands 21 are here shown as attached to one end of the cross member 20^a of the frame 20. The cross member 20^b at the other end of the frame 20 is here shown as provided with a U-shaped extension 20^c carrying the springs 23 to which the ends of the wires 21 are attached; such wires extending through suitable holes in the end member 20^b. The springs 23 serve to give the strands 21 a suitable tension.

The frame 20 is provided at its corners with depending vertical members 24, and the lower ends of these members on each side are connected by tension members 25 serving to brace against the tension of the strands 21. The vertical members 24 on each side are joined by a rod 25^a, the ends of such rods being attached to the vertical members 24 substantially at their center points. The rods 25^a are adapted to slide in the bearing members 26 carried by the ends of the cross members 27 which, in turn, support the lower section 11 of the furnace, such members 27 being carried by the pipe frame 12.

I shall now describe the work pressing means. As pieces of work come from the furnace in heated condition, it is frequently desirable to press the same or hold the same in a certain position so that they will cool in correct shape. For example, a flat piece of work, such as a plaque, is sometimes slightly bent or warped by the heat of the furnace and it may be desirable to press the same and hold it in flattened position until it cools. Such pressing means I have here shown as including a work support 30 below the supporting and conveying strands 21. As shown in Fig. 5, the work support 30 is mounted on a post 31 vertically movable in the tubular member 32 mounted on the plate 33 which, in turn, is slidably mounted on the pipe frame 12. Means are provided for adjusting the pressing means longitudinally, said means including a depending block 34 carried by the plate 33 and a screw 35 inserted into a threaded opening 36 in said block. 37 indicates a bearing member carried by the cross-bar 12^a of the pipe frame. One end of the screw 35 is provided with a handle 38 for rotating the same. By rotating the screw 38, the plate 33 may be slid longitudinally upon the side members 12 of the pipe frame, thus permitting longitudinal adjustment of the work support 30 longitudinally in order to place the same under a piece of work resting on the conveyor members 21. The plate 33 carries two vertical members 40 and 41 arranged on opposite sides of the conveyor elements 21. Hingedly attached to the upper end of the member 40 is a plate 42 adapted to carry

on its upper side the cover member 43, here shown as carried by two posts 44, 44, the member 43 being mounted for slight vertical movement on the posts 44, 44, and the springs 45 being interposed to yieldingly 70 press the member 43 downwardly. The member 43 includes a removable face plate 43^a attached to the member 43 by means of the undercut shoulders 43^b. The face plate 43^a, as shown in Fig. 4, is adapted 75 for easy removal to permit exchange. For example, in heating a plaque, as shown in Fig. 8 and indicated by 50, the bottom of the face plate 43 is preferably provided with a concavity 43^c adapted to accommodate 80 more or less the upper surface of the plaque 50. If desired, the present means may also be used for embossing, stamping, lettering, or designing articles.

Means are provided for raising the work support, said means including a transversely mounted rotatable shaft 60 carried by the depending member 61 mounted on the plate 33 and having its inner end rotatably supported in bearings 64 in the lower end 32^a 90 of the tubular member 32. 65 indicates an eccentric mounted on the inner end of the shaft 60 and lying below the post 31, so that rotation of the shaft 60 accomplished by the handle 66 on the end of the crank 67, 95 tends to rotate the eccentric 65 to raise and lower the post 31, and, consequently raise and lower the work support 30. The work support 30 is provided with grooves 70 adapted to accommodate the conveyor 100 strands 21 when the work support 30 is raised. The plate 42 being hingedly attached to the upper end of the vertical member 40 permits the same to be raised to open position, as shown in Fig. 1, or lowered into closed position, as shown in Fig. 5. When in closed position, the locking bar 71 provided with a hole 72 is adapted to be swung down over the locking pin 73 to hold the plate 42 in closed position.

80 indicates a work holder adapted to rest on two of the conveyor strands 21 and carry a piece of work such as, for example, a plaque 50. In the operation of the device, when a piece of work such as a plaque 50 is 115 removed from the furnace and still in heated condition, the plate 33 is adjusted longitudinally by means of the screw 35 until the work support 30 is directly beneath the piece of work. The plate 42 is then closed, and a more perfect adjustment may be made so that when the work support 30 is raised by means of the handle 66, the piece of work lying on the carrier 80 will be pressed up 120 firmly against the cover plate 43^a and the piece of work on the carrier 80 held in this position until the same cools. When the work support 30 is thus raised upwardly, the grooves 70 therein will accommodate the 125 conveyor strands 21.

In the device shown in Fig. 1, the frame 20 carrying the conveyor strands 21 is adapted to be reciprocated by hand. Such reciprocation, however, may be accomplished 5 automatically. For example, as shown in Fig. 3, the frame of somewhat different form may be as indicated by 120, the same being reciprocably mounted on the rollers 121 carried by the vertical members 122. In Fig. 10 3, I have shown somewhat diagrammatically, means for automatically reciprocating the frame 120. For example, such means may include a reversible electric motor 123 driving a worm 124 which, in turn, drives a gear 125 on the shaft 126, such shaft also carrying a pinion 127 meshing with a gear 128 on the shaft 129 which also carries a gear 130 meshing with a rack bar 131 on the side of the frame 120. The current is adapted to 15 be supplied to the motor 123 from the line wires 134. The armature circuit is indicated by the wires 150, 151 and the field circuit by the wires 152, 153. 135 indicates a reversing switch adapted to be engaged by 20 the vertical posts 136 on the ends of the frame 120, to reverse the flow of current in the armature circuit. In the operation of the device, the frame 120 at the end of its travel, is adapted to reverse the switch 135 25 on engagement of one of the posts 136 with one end of the bar 137 carried by the switch, so that at each end of its travel, the motor will be reversed, thus causing reverse movement of the frame 120.

35 In Figs. 6 and 7, I have shown modified forms of work conveyor or support. As shown in Fig. 6, instead of providing strands 21 extending from one end of the frame to the other, I provide at each end a plurality 40 of bars similar to Fig. 1 extending inwardly. As shown in Fig. 6, the member 222 is similar to one of the members 20^a and 20^b of the frame 20, as shown in Fig. 1, and it is to be understood that there are a plurality of 45 bars 221 extending inwardly from each of said ends.

The inner ends of the member 221 are 50 preferably provided with holes 223 to support connecting bars (not shown). In the modified form of work conveyor or support, as shown in Fig. 7, I have substituted for the wire strands 21 a plate 321 provided with holes 322 therein.

55 While I have shown and described certain embodiments of my invention, it is to be understood that it is capable of many modifications. Changes, therefore, in the construction and arrangement may be made 60 without departing from the spirit and scope of the invention as disclosed in the appended claims, in which it is my intention to claim all novelty inherent in my invention as broadly as possible, in view of the prior 65 art.

What I claim as new, and desire to secure by Letters Patent, is:

1. A ceramic furnace having a heating chamber, and a reciprocable frame having work supporting strands extending entirely 70 through the heating chamber.

2. A ceramic furnace having a heating chamber, and a reciprocable frame having a plurality of parallelly arranged work supporting strands extending through the heat- 75 ing chamber.

3. A ceramic furnace having a longitudinal heating chamber extending therethrough and a reciprocable frame having work supporting strands extending entirely through 80 the heating chamber.

4. A ceramic furnace having a longitudinal heating chamber extending therethrough, and a reciprocable frame having a plurality of parallelly arranged work supporting 85 means extending through the heating chamber.

5. A ceramic furnace having a longitudinal heating chamber extending therethrough, and a reciprocable frame having a plurality 90 of parallelly arranged work supporting strands extending through the heating chamber.

6. A ceramic furnace; work supporting and conveying strands extending through 95 said furnace; and means for pressing work pieces, said means including a work support below the supporting and conveying strands, a cover member above the supporting and conveying strands, and means for moving the work support upwardly to lift the work piece from the supporting and conveying strands and press the same against said cover member, said work support being provided with means to accommodate the supporting and conveying strands when it 100 is moved upwardly.

7. A furnace as claimed in claim 6, in which the cover member is yieldingly pressed downwardly against the work support. 110

8. A device as claimed in claim 6, with means for adjusting the work pressing means longitudinally with respect to the furnace.

In testimony whereof I hereunto set my hand this 28th day of November, 1928. 115

JOSEPH A. DEDOUCH.
